US0D1094871S

(12) **United States Design Patent** (10) **Patent No.:** **US D1,094,871 S**
(45) **Date of Patent:** **** Sep. 23, 2025**

(54) **SKINCARE APPLICATOR**

(71) Applicant: **Practical Science LLC**, San Jose, CA (US)

(72) Inventor: **Raana Haghigheh Kashani Gregg**, San Jose, CA (US)

(73) Assignee: **Practical Science LLC**, San Jose, CA (US)

(*) Notice: Patent file contains an affidavit/declaration under 37 CFR 1.130(b).

(**) Term: **15 Years**

(21) Appl. No.: **29/852,886**

(22) Filed: **Sep. 9, 2022**

(57) **CLAIM**

The ornamental design for a skincare applicator as shown.

DESCRIPTION

FIG. 1 is a perspective view of a skincare applicator according to the claimed design.

FIG. 2 is a top plan view of the skincare applicator according to the claimed design.

FIG. 3 is a bottom plan view of the skincare applicator according to the claimed design.

FIG. 4 is a right-side plan view of the skincare applicator according to the claimed design, the left-side plan view is a mirror image thereof.

FIG. 5 is a front side plan view of the skincare applicator according to the claimed design.

FIG. 6 is a back side plan view of the skincare applicator according to the claimed design; and,

FIG. 7 is an exploded perspective view of the skincare applicator according to the claimed design showing the applicator handle and the applicator pad.

The broken lines illustrate portions of the skincare applicator that form no part of the claimed design.

1 Claim, 7 Drawing Sheets
